(57) **CLAIM**

The ornamental design for a bone ball pet toy, as shown and described.

DESCRIPTION

FIG. 1 is a top-front-left perspective view of a bone ball pet toy showing my new design;

FIG. 2 is a bottom-front-left perspective view thereof;

FIG. 3 is a top-rear-right perspective view thereof;

FIG. 4 is a bottom-rear-right perspective view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is a right elevational view thereof; and,

FIG. 10 is a left elevational view thereof.

The broken lines showing rope ends in FIG. 1-10 are included for the purpose of illustrating environmental structure and form no part of the claimed design.

1 Claim, 10 Drawing Sheets(56)
